UNITED STATES PATENT OFFICE.

STANLEY BYERS, OF BEDFORD, INDIANA.

CUSHIONING HANDLE FOR PNEUMATIC TOOLS.

Application filed June 17, 1926. Serial No. 116,699.

This invention relates to an improvement in cushioning handles for pneumatic tools such as stone-working chisels or the like.

The object of the invention is to provide a handle for pneumatic tools which is preferably in the nature of a casing so as to enclose the barrel of the tool, the handle having embodied therein a number of springs which are interposed between the barrel of the tool and the casing in such a novel and effective manner as to take up and absorb the shocks and jars incident to the chiseling, hammering, or other operation which the tool is carrying out, thereby relieving the operator of the severe strain which he would undergo were he to hold the barrel or cylinder of the tool directly.

A further object is to provide a cushioning handle having these advantages and capacities and which also has embodied therein a novel means for normally holding the chisel, bit, or hammer in place but out of the field of operation of the piston operating in the barrel of the pneumatic appliance, the means for positioning the chisel, bit or hammer being yieldable so that when the chisel, bit or hammer is applied to the work it will be automatically forced back into the field of operation of the piston or hammer operating in the barrel, thereby causing operation of the chisel, bit or hammer.

Other objects and advantages reside in certain novel features of the construction, arrangement and combination of parts which will be hereinafter more fully described and particularly pointed out in the appended claim, reference being had to the accompanying drawings forming a part of this specification, and in which:

Figure 1 is a view in side elevation showing a pneumatic tool equipped with a cushioning handle embodying the present invention.

Figure 2 is a view thereof in central longitudinal section, parts being shown in elevation for the sake of simplicity and illustration.

Figures 3 and 4 are sectional views on the lines 3-3, and 4-4, respectively, of Figure 2.

Figure 5 is an enlarged view showing the coupling handle in section and the parts contained therein in elevation, and

Figure 6 is a fragmentary perspective view of the shank of the bit or chisel.

Referring to the drawings wherein for

the sake of illustration the numeral 1 designates generally a pneumatic tool of standard and conventional construction and embodying a barrel or cylinder 2 having a working chamber 3 in which a piston 4 reciprocates under the action of the fluid pressure such as compressed air or the like. The air is supplied from an air line 5 through a connection 6 into a removable head 7 provided at one end of the barrel. The air passes into the working chamber 3 in the usual manner. It is to be understood that while the present invention is shown applied to the Dallett tool it is not restricted in its application to this particular type of tool but may be used in any of the standard or conventional pneumatic tools.

The present invention proposes the provision of an annular shoulder 15 on the outside of the barrel. One end of a coil spring 16 engages one side of the shoulder 15 and one end of a coil spring 17 engages the opposite side thereof. The coil springs 16 and 17 are contained within a tubular cushioning handle 18 which also affords a casing for the tool and springs. At its forward end the tubular handle 18 is internally enlarged, as at 19, and one end of this enlargement presents a shoulder 20. The end of the spring 16 opposite that engaged with the collar 15 engages the shoulder 20. The tubular handle 18 includes two sections, one designated at 18^a and the other designated at 18^b, the sections 18^a and 18^b being threadedly connected, as at 21. The inner end of the section 18^b presents a shoulder 22 with which a washer 23 engages. The washer 23 serves as an abutment for the end of the spring 17 opposite that engaged with the collar 15. With this arrangement the pneumatic tool 1 is shiftable within the combined casing and handle 18 but its axial shifting movement is restricted by the springs 16 and 17. By thus mounting the tool within the handle the shocks and jars incident to the chiseling, hammering, or other operation, are absorbed and taken up, thereby relieving the operator of the strain which would otherwise undergo. Of course, it is to be understood that the operator in using the tool grasps the outside of the combined casing and handle 18.

In the forward end of the barrel or cylinder 2 a bushing 25 is provided and this bushing 25 slidably receives the rounded portion 26 of the shank of the bit, chisel, or hammer,

designated at 27. The bit, chisel, or hammer also has a section 28 which is of non-circular form and in the present embodiment is squared. In order to prevent the bit 27 from dropping out of the socket of the handle 18 and out of the socket which the bushing 25 provides, the squared section 28 of the shank thereof has a peripheral recess 30 of rounded form and this recess 30 is engaged by a spring pressed pawl 31 and also by a pivoted detent 32, the spring pressed pawl 31 and the pivoted detent 32 being carried by the enlarged portion 19 of the combined handle and casing. When the pawl 31 and detent 32 engage the portion 38 of the shank of the bit, they hold the bit in the position shown in Figure 2, that is, in inoperative position, that is to say the inner end 33 of the shank of the bit is spaced from the outer end 34 of the reduced extension 35 of the piston or hammer. The result of this arrangement is that even though the piston 4 be reciprocated its reduced extension which constitutes its impact member, will not strike the end 33 of the bit and will not actuate the bit unless and until the bit is pressed against the work and its inner end 33 forced inwardly into the field of operation of the piston or hammer of the pneumatic tool. In order to insure the automatic inoperative positioning of the bit, a light coil spring 40 is provided, the coil spring 40 engaging the bushing 25 and a shoulder 46 formed at the juncture of the rounded portion 26 and the squared portion 28 of the shank of the bit. This coil spring 40 is sufficiently tensioned to ordinarily move and hold the bit 27 in such position that the spring pressed pawl 31 and the detent 32 will co-act with the recess 30 thereof. The advantage of having a spring to hold the bit out of the normal field of operation of the reciprocating element of the pneumatic tool resides in the fact that the bit will not be projected or shot from the tool since it will not be actuated until it is pressed against the work. This advantage is in addition to the cushioning action of the handle.

I claim:—

In combination with a pneumatic tool having a barrel, a piston reciprocable in the barrel and having an impact member at its forward end, said barrel having a socket, a bit having a portion of its shank receivable in the socket and adapted to be engaged with the impact member of the piston when pressed inwardly, a combined casing and handle enclosing the barrel and having a socket receiving a portion of the shank of the bit, releasable means co-operable with the bit for holding it in inoperative position out of the field of action of the impact member of the hammer, and a spring engaging the barrel of the hammer and the bit to urge the bit outwardly out of the field of operation of the impact member of the hammer until and unless the bit is pressed against the work.
